COOLING SYSTEM

Frank P. Illsley, Muskegon, Mich., assignor of
one-half to Arthur H. Boettcher, Evanston,

Application October 21, 1936, Serial No. 106,720.

27 Claims. (Cl. 123—174)

This invention relates to cooling systems for internal combustion engines, and has to do with a cooling system particularly adapted for use with automobiles and with a valve for use in such a system.

The use of a cooling system for an automobile engine, and which system is normally closed to the atmosphere, possesses numerous advantages over the cooling systems now in use and which are at all times open to the atmosphere. By having the cooling system closed to the atmosphere, loss of water or anti-freeze is prevented, the engine may operate at higher temperatures than with a normally open cooling system with resulting increase in efficiency, and the radiator may be of smaller capacity than in the normally open cooling system, thus effecting a saving in cost of the radiator. While a closed cooling system is preferable to a normally open cooling system, for the reasons noted, there are certain difficulties attendant upon the use of a closed system.

In a closed system considerable pressure may build up within the system, including the radiator, accompanied by an increase in temperature which may become sufficiently high to soften the solder of the joints, and under unfavorable conditions this pressure may become so great as to cause rupture of the radiator or blowing off of the hose connection. In order to limit the pressure to a safe maximum value, it is necessary to employ a relief valve. Relief valves of ordinary type are not suitable for this purpose, due to the small area of the valve exposed to the pressure within the system and to the relatively large area of contact between the valve and its seat. A relief valve used in a cooling system is subject to the liquid and vapors of the system and soon becomes fouled or corroded, with the result that the valve member sticks to its seat and will not open at the desired safe and predetermined maximum pressure. A further difficulty in using a closed system is that if the filler cap or equivalent member is removed for replenishing the water or liquid in the radiator when the system is under appreciable pressure, there is great danger of the person removing the cap being seriously scalded by water and steam blowing out through the filler neck or opening.

One of the main objects of my invention is to provide a thoroughly practical and highly efficient cooling system for internal combustion engines, particularly well suited for use with automobile engines, which system is normally closed to the atmosphere and is free of the above noted

difficulties.

Another object is to provide a valve which is

adapted to withstand water and steam pressure

Figure 14 is a view similar to Figure 10 illustrating a fifth modification of my invention.

This application is a continuation in part of my copending application, Serial No. 639,317, filed October 24, 1932, which has matured into Patent No. 2,067,924, issued January 19, 1937.

I have illustrated the cooling system of my invention, by way of example, as applied to an internal combustion engine E which is of known construction and comprises a water jacketed cylinder block c and a cylinder head d, also water jacketed. This engine has associated therewith a cooling system comprising a radiator r which is, in general, of known construction and is provided with a top tank t and a bottom tank s. Tank s is provided with an outlet fitting f in which is mounted a non-return valve g of known type. Fitting f is connected by a length of hose h to intake member i of a pump p, the discharge of which is connected by a manifold m to the cylinder block c. This pump may be driven in any suitable manner, and is shown as being driven from the timing gearing o of the engine. An outlet neck n extends from the head d and has a reducer k suitably mounted on its outer end, this reducer being connected by a length of hose l to an inlet fitting a of the top tank t and opening thereinto. The pump p serves to produce circulation of the water or cooling liquid through the cooling system in a known manner.

Neck n is suitably shaped, at its upper end, to provide a seat for a disc valve v operated by a bellows thermostat u, the lower end of which is suitably secured at b in neck n. The valve v and the bellows-thermostat u are properly proportioned to balance the pressure so that the valve is controlled by temperature only. The valve v serves to close the upper or outer end of neck n until the water or cooling liquid of the engine jacket reaches a predetermined temperature sufficiently high to assure proper starting and operation of the engine. The valves g and v cooperate to segregate the portion of the cooling system therebetween from the radiator, so that relatively high pressures, with resulting increase in temperature, can be built up in the system between these two valves without subjecting the radiator to objectionably high pressures and temperatures.

Neck n is provided with an offset forming a valve chamber i in which is mounted a ball float valve 2 which controls a vent opening 3 in the top of chamber i. Downward movement of valve 2 in the chamber is limited by a pin 4 projecting into the lower end of the chamber. When the cooling system is properly filled with cooling liquid, valve 2 occupies the position of Figure 1 and closes opening 3 to the atmosphere. In this figure the cooling liquid is at the normal level therefor when the engine is hot.

When the engine cools down, with corresponding cooling off of the cooling system, the cooling liquid in the system falls materially below the level thereof shown in Figure 1, and a partial vacuum may be produced in the cooling system. Under such conditions, valve 2 will be lowered so as to uncover the opening 3 and admit air therethrough into the system to satisfy the partial vacuum produced.

It is desirable, particularly in a closed cooling system, that an expansion space be provided to accommodate the expansion of the cooling liquid, when heated, and the vapors generated by heating of the liquid. The tank t is provided with a filling tube 5, the lower portion of which is

bent laterally at 5a to define an opening normally closed by a flap valve 6 pivoted at its upper edge to the tube 5. The tube 5 is secured through the top wall of the radiator so as to form therewith a fluid-tight and pressure-resistant closure. A threaded collar 7 is secured about the upper portion of tube 5 and receives a closure cap 8 which screws onto the collar and forms therewith, and with the upper end of the tube, a fluid tight and pressure-resistant closure. The filling tube serves to limit the height to which the tank t can be filled by liquid introduced through the tube 5 and assures that an adequate expansion space 9 is provided above the liquid in the tank. It will be understood that the level of the liquid shown in Figure 1 is approximately the maximum height to which the water or like cooling liquid introduced through the tube 5 will rise when the engine is cold. After the engine has been in operation for a considerable time, the water or cooling liquid in the system becomes heated and expands so that the expansion space will be correspondingly smaller than the space shown in Figure 1.

A cup-shaped valve casing 10 is mounted at the back of radiator tank t and communicates therewith through a nipple 11 extending from the casing and secured in a collar 12 defining an opening through the back wall of the tank. The top of casing 10 is closed by a circular diaphragm 13 of resilient metal, brass being suitable for this purpose. The edge portion of this diaphragm is tightly secured in a bead 14 formed by turning down the edge portion of casing 10 so as to form a fluid-tight and pressure-resistant closure between the edge of the diaphragm and the casing. The main portion of the diaphragm is depressed so as to fit into the upper portion of casing 10 and be held thereby in concentric relation to the casing. This diaphragm is preferably provided with a plurality of concentric corrugations extending about a valve element 15 of annular shape and defining a circular outlet opening at the center of the diaphragm. Conveniently, the element 15 is formed by turning down the center portion of the diaphragm as shown. The valve element seats upon the upper flat face of a valve seat member 16 extending upwardly from the casing 10 centrally thereof, this seat member being formed integral with the casing. Diaphragm 13 acts, by its inherent resiliency, to normally hold valve element 15 in edgewise contact with the flat seat of member 16 so as to form therewith a fluid-tight closure. The under side of diaphragm 13 is of much greater area than the outlet opening or port defined by the valve element 15 and is subjected to the pressure within expansion space 9, that is, to the pressure within the cooling system. Since member 15 has edge contact with valve seat member 16, the area of contact between these members is quite small and does not provide lodgment for foreign materials contained in the cooling liquid, nor is the area of contact of sufficient extent to render possible sticking together of the valve and the valve seat due to corrosion.

Normally, the cooling system is completely closed or sealed to the atmosphere. In the operation of the engine, the cooling liquid is heated and vapors are evolved so that pressure is built up within the system and, consequently, within the space 9 and the valve casing 10. The pressure exerted by the diaphragm 13 may be such that the valve member 15 starts to move away from the seat member 16 when a definite and

predetermined pressure exists within the cooling system. It will be understood that the pressure at which the valve starts to open may be varied within limits, according to the particular system with which the valve is to be used. Ordinarily, I find that a valve which will start to open at a pressure of approximately five pounds within the cooling system is suitable for most systems. This pressure is not often attained and the cooling system remains closed to the atmosphere under ordinary conditions, except at such time as undesirable overheating of the system may occur, with resulting increase in the vapors generated in the expansion space. Under such conditions, the pressure in the expansion space and exerted against the under face of diaphragm 13, serves to raise the valve member 15 so as to vent the expansion space to atmosphere, when the pressure within the space reaches the predetermined maximum value.

The diaphragm 13 is so made as to have a very rapid natural period of vibration. When valve member 15 is raised from its seat 16, a small amount of vapor escapes to the atmosphere with a resultant slight drop in pressure beneath the diaphragm 13 which acts to immediately return valve member 15 to its seat, this member being then again raised by the pressure which builds up the required extent instantaneously, this vibration of the member 15 continuing during escape to the atmosphere of the vapors, that is, during the time that the pressure within the expansion space exceeds the permissible maximum. In consequence of the escaping vapor, the diaphragm 13 and the member 15 are vibrated at high speed and produce a whistling noise of high pitch and which is very penetrating. The valve thus serves as an audible signal to notify the operator of the automobile that the supply of liquid in the cooling system needs replenishment. Since the cooling system is normally closed to the atmosphere, no vapors escape therefrom under ordinary conditions, so that there is no loss of cooling liquid or of antifreeze mixed with the liquid. The closed system is of particular advantage in conserving volatile antifreeze, such as alcohol, and also has the advantage of eliminating loss of cooling liquid due to evaporation, splashing or the like, the only loss of liquid from the system, under ordinary conditions, being due to such leakage as may occur through connections and stuffing boxes. The use of a closed cooling system thus has the advantage that it is necessary to replenish the cooling liquid only occasionally and not quite frequently, as in the ordinary type of cooling systems now commonly used and normally open to the atmosphere.

As clearly shown in Figure 1, the effective cross sectional area of the nipple or conduit 11 through which fluid under pressure is admitted from the top tank of the radiator into the valve casing, is not in excess of, and preferably somewhat less than, the effective cross sectional area of the outlet opening 15 of diaphragm 13. In all of the forms of the valve illustrated, the effective cross sectional area of the outlet opening is at least equal to the effective cross sectional area of the opening or conduit for admitting fluid under pressure into the valve casing, as clearly shown in the drawings. This is advantageous in that it eliminates possibility of building up, within the valve casing, of a pressure of such high value as to move the diaphragm in opening direction an excessive distance such as to impart to the

diaphragm a permanent set such as would hold the valve member carried by the diaphragm in open position, thus establishing permanent communication between the exterior of the cooling system and the atmosphere.

The filling tube 5 and the flap valve 6, in addition to limiting the extent to which liquid poured into the radiator can rise, also effectively prevents the possibility of scalding of the driver of the automobile, or of an attendant, due to inadvertent removal of the closure cap of the filling tube. If there be appreciable pressure within the cooling system, this pressure is effective to close the valve 6 so as to prevent escape of contents of the system through tube 5 upon removal of cap 8. When the tube 5 is filled with water or cooling liquid, if the pressure exerted on valve 6 from within tank 7 is greater than the pressure exerted by the column of liquid in the tube 5, the valve 6 remains closed until the pressure within the tank is less than the pressure exerted by the column of liquid in tube 5, at which time there is no danger of the water or cooling liquid being forcibly ejected out of tube 5 by the pressure within the tank.

The accumulation of pressure within the cooling system permits of the water or cooling liquid being heated to a higher temperature than would otherwise be possible, so that the engine operates at a higher temperature than with a cooling system normally open to the atmosphere. This has the advantage of decreasing the fuel consumption of the engine with resulting increase in efficiency thereof from the standpoint of fuel consumption. The pressure built up in the closed cooling system may be utilized for operating mechanisms associated with the cooling system, such as shutters, which are commonly employed for regulating the flow of air through the radiator for cooling the water therein. For this purpose I provide a depression in the front wall of tank 7, which depression constitutes a pocket 20 communicating with the interior of the tank through an opening 21. A diaphragm 22 of suitable material is secured to the front wall of the tank by a securing ring 23, or in any other suitable manner, and provides a movable wall closing the outer side of the pocket. A connecting member 24 is suitably secured to the diaphragm 22, centrally thereof, this member being adapted for connection to a suitable mechanism, such as shutters disposed adjacent the radiator. It will be understood that the diaphragm 22 may be employed for operating any suitable mechanism exterior of the radiator.

It is desirable that the liquid in the cooling system be replenished from time to time to compensate for cooling liquid which may be lost by leakage or by escape of vapor to the atmosphere through the valve, though loss from the latter cause is extremely slight under ordinary conditions. A supply tank 25 is suitably supported in such manner that the bottom of this tank is above the normal liquid level in the radiator tank 7. This tank is provided with a filling neck 26, normally closed to the atmosphere by a screw cap 27. An outlet nipple 28 extends from the bottom of tank 25 and is connected by a length of hose 29 to a nipple 30 opening into the lower end of a float chamber 31 within the top radiator tank 7. Nipple 30 is secured to the underside of bottom wall 32 of float tank 31, which bottom wall is provided with an inlet opening 33 controlled by a valve 34 carried at the lower end of a stem 35 depending from a float 36 in float

chamber 31, which chamber communicates through openings 36 with the interior of tank *t*. A stem 37 extends through the upper end of float tank or chamber 31 and carries, at its upper end, 5 a disc head 38. A bimetallic thermostat strip 39 has its inner end disposed beneath head 38, the outer end of this strip being secured to a bracket 40 secured to the inner face of the back wall of tank *t*. An elbow 41 is secured through 10 the top wall of tank *t* and opens into the expansion space 9. This elbow is connected by a length of hose 42 to a fitting 43 which screws into a boss 44 opening through the top of tank 25. When the engine is cold, the thermostat 15 strip 39 holds the head 38 in its uppermost position, thus holding the valve 33 seated and preventing entry of cooling liquid into tank *t* through nipple 30. After the engine has been 20 operated for an appreciable time and the cooling system has been heated to the proper operating temperature, strip 39 becomes bowed downward so as to release the head 38 and, under such conditions, if the level of the liquid in tank 9 falls below the level of Figure 1, valve 33 opens 25 and admits sufficient liquid from tank 25 to restore the liquid level in tank *t*. It is desirable that this replenishment of the liquid in the cooling system occur when the system is at operating temperature, since, if additional liquid were admitted to the system when cold, the expansion of this additional liquid when heated might result in increasing the pressure in expansion space 9 to an undesirable extent, thus causing premature opening of the relief valve and the loss of 30 more or less liquid rather than vapor only. In this connection it is noted that the pressure at which the relief valve opens bears an approximate relation to the operating temperature of the engine, as above pointed out. While I preferably provide the tank 25 and associated parts 35 for automatically replenishing the liquid supply in the cooling system, this is not essential and these parts may be omitted if desired. Also, if desired, the valves *v* and 2, and associated parts, 40 may be omitted, as well as the valve *g*.

In the form of my invention illustrated in Figure 2, top wall 50 of the tank *t* is provided with a filler opening defined by a collar 51. A threaded ring 52 is secured about the collar 51 45 so as to form a fluid-tight and pressure-resistant closure therewith. Ring 52 receives a flange nut 53 which screws thereon. A cylindrical filling tube 54 extends through ring 52 and downwardly within tank *t* to within a short distance of the bottom wall thereof. This tube is provided, at 50 its upper end, with an outwardly extending flange 55 which is tightly clamped between the upper face of ring 52 and flange 56 of nut 53, so as to provide a fluid-tight and pressure-resistant closure about the flange of the tube. Flange 56 of nut 53 is interiorly threaded for reception of a threaded closure cap 57 screwing into flange 56, this cap having an outer flange 58 which seats upon a gasket 59 confined between flanges 56 and 58 so as to form a fluid-tight and pressure-resistant closure therebetween. Preferably, flange 55 of tube 54 is suitably secured to flange 56 of nut 53. By removing nut 53 the tube 54 may be removed so that there is no air 60 trapped in tank *t* which may then be filled more quickly than when tube 54 is in place. The cap 57 is provided with an L-shaped duct 60 extending from a central cavity 61 in the under face of the cap and opening through the under face of flange 58. Normally, the outer end of

duct 60 is sealed by the gasket 59. If the cap 57 is screwed out of flange 56 for a short distance, the outer end of duct 60 is moved out of contact with gasket 59 and the duct then serves to vent any pressure within the tube 54 to the atmosphere. This serves as a warning that appreciable pressure exists within the tank *t* and the cap 57 should not be removed until the pressure within the tank has dropped to atmospheric pressure, or approximately so, which can be determined by the velocity of the air or vapor escaping through the duct 60.

Top wall 50 of the tank is provided with an opening which accommodates a valve structure 62, quite similar to the valve structure of Figure 15 1, wall 50 being depressed about this opening to provide a flange 63 forming a seat for bead 64 of valve structure 62. This valve structure comprises a lower casing section 65 of cup-like shape, and an upper casing section 66, also of cup-like 20 shape. A metal diaphragm 67 extends across the casing section 65, the main or body portion of this diaphragm being slightly depressed so as to fit into section 65 in centered relation thereto. The edge portion of diaphragm 67 constitutes 25 a flange element which extends between the casing sections 65 and 66, which sections are secured tightly together by the bead 64 formed by turning downwardly and inwardly the peripheral portion of casing section 65. In this manner the 30 two sections of the casing are secured tightly together and the edge portion of the diaphragm is clamped tightly between the casing sections so as to form therewith a fluid-tight and pressure-resistant closure extending about the circumference of the valve casing. The diaphragm 67 is formed of resilient sheet metal, preferably brass or bronze, and is preferably provided with a plurality of concentric corrugations as shown.

The diaphragm is pierced centrally and is 40 turned downwardly to provide an annular valve member 68 defining a circular outlet opening. This member 68 is quite thin, being of the same thickness as the diaphragm 67, and has edge contact with a flat valve seat provided by a seat member 69 extending inwardly from the central portion of casing section 65 and conveniently formed integral therewith. The diaphragm 67 normally acts, by its inherent resiliency, to hold valve member 68 45 against the seat of member 69 so as to form a fluid-tight closure therewith. Casing section 65 50 communicates with the expansion space in tank *t* through openings 70 in the lower wall of section 65, or in any other suitable manner. Section 55 66 of the valve casing is provided with an outwardly offset element 71, in which is secured a tube 72 opening to atmosphere at a suitable location. This section 66 may also be provided with an opening 73 to atmosphere, in front of 60 which, within section 66, and suitably secured thereto, is disposed a baffle member 74.

The area of the diaphragm 67 exposed to the pressure within the tank *t* is much greater than the area of the outlet opening or port defined 65 by the valve element 68, and, since this element has edge contact with the seat of member 69, there is no possibility of the valve sticking closed due to corrosion or other causes. When the pressure within the cooling system reaches the predetermined maximum, the pressure exerted 70 against the under face of diaphragm 67 lifts the valve member 68 from its associated seat, thus venting the tank *t* to atmosphere and producing an audible signal of high pitch and which can 75

readily be heard by, and will immediately attract the attention of the driver of the automobile.

When the cooling system cools off, after the engine has been in operation for a considerable time, a partial vacuum will be produced within the tank *t*, due to condensing of the vapors therein. Under certain conditions, it may be desirable to relieve this partial vacuum. For this purpose, I provide a cup valve *75* which normally seats accurately in valve seat member *69*, at the under face thereof. This cup-valve *75* is tightly secured to a pin *76* having a loose sliding fit through member *69*. An expansion coil spring *71* is mounted about pin *76* and bears, at its lower end, on the upper face of member *69*, the upper end of this spring being suitably secured to the pin. Under normal conditions, the cup valve *75* remains in closed position. If a partial vacuum is produced within the tank *t*, air flows through tube *72* into casing section *66* and thence about the pin *76* so as to cause opening of cup valve *75*, by atmospheric pressure exerted upon the upper face thereof, thus permitting air to flow into the tank *t* until the partial vacuum therein has been satisfied, or approximately so, it being understood that the spring *71* merely serves to raise the valve *75* into seating position and does not exert any considerable pressure for holding this valve closed. After the partial vacuum within the tank *t* has been satisfied, the valve *75* returns to its normal or closed position.

In Figure 2, bead *64* of the valve *62* is soldered or otherwise secured in the depression defined by the downwardly bent flange or element *63* of wall *50*.

In Figure 3 wall *50* is provided with a depressed element *63a* of approximately L-shape, in vertical section, this element defining a circular recess for reception of bead *64* of valve *62* and a horizontal flange upon which seats a gasket *80*. Bead *64* seats upon the gasket and the valve is held tightly in position by a pressure bar *81* provided adjacent its ends with oppositely directed notches *82* which engage about reduced necks *83* of headed studs *84* riveted or otherwise suitably secured to wall *50* at opposite sides of element *63a*, the studs being in alignment diametrically of valve *62*. Bar *81* serves to hold the valve *62* in position and exerts sufficient pressure thereon to assure a fluid-tight and pressure-resistant closure about bead *64* of the valve. Preferably bar *81* is provided with an extension *85* constituting a grip for convenience in removal and replacement of the bar. In the form of Figure 3, the valve *62* can be removed and replaced with facility. Otherwise, the construction and operation of the valve is similar to that of the valve shown in Figure 2.

In Figure 4 the valve *62a* is of quite similar construction to the valve of Figure 2, but is reversed relative thereto and the lower casing section *66a* is provided with an offset element *11b* disposed in the vertical plane of element *11a* of the upper casing section *65a*. Valve seat member *69a* is shaped slightly differently than in Figure 2 and is provided with a central upwardly extending and rounded element or depression *69b*. With the exceptions noted, the construction and operation of valve *62a* is similar to that of valve *62*, it being noted, however, that the air inlet valve *75* and associated parts, and the baffle *14* of valve *62*, are omitted from valve *62a*.

Nipples *86* and *87* are suitably secured in offsets *11a* and *11b* of the casing of valve *62a*, respectively, these nipples also being secured, at

their outer ends, in a mounting plate *88* secured by screw means *89*, or in any other suitable manner, to the back wall of upper radiator tank *t*, a gasket *90* being disposed between this wall and the plate *88*. Nipple *86* communicates with a tube *91* which extends upwardly into a filling neck *92* of the radiator and nipple *87* communicates with an outlet tube *93* which extends to the exterior of the radiator and is open to the atmosphere at a suitable location. The diaphragm *10* of valve *62a* is subject to the pressure within the tank *t*, by means of tube *91* and nipple *86* and, when this pressure reaches a predetermined maximum, the valve opens and vents the tank to atmosphere through nipple *87* and tube *93*. The valve serves as an audible signal in the manner previously described.

Filler neck *92* is normally closed by a cap *95* at the under face of which is disposed a concaved disc *96* which seats flat upon a flange *97* formed by the turned-in upper end portion of neck *92*. The disc *96* comprises an upper metal disc *96a* and a lower disc *96b* of fiber or rubber and which forms a fluid-tight closure with flange *97*. The cap *95* is provided with a plurality of lugs depending therefrom, one of which is shown at *98*. Each of these lugs is provided with a pin *99* disposed to engage into a bayonet slot *100* formed in a flange *101* depending from the inner edge of flange *97*. When the cap is in full closed position, the metal disc *96a* is placed under tension and forces the disc *96b* tightly against flange *97* so as to form therewith a fluid-tight and pressure-resistant closure. The cap and the filler neck are, in general, of known construction and need not be illustrated nor described in greater detail. It is pointed out, however, that I provide each of the bayonet slots *100* with an upwardly extending recess *100a* adapted for reception of pin *99*. If there is appreciable pressure within the tank *t*, when the cap *95* is turned in opening direction and through a short distance, pin *99* engages into recess *100a*, due to the pressure exerted on the under face of disc *96*, and stops opening of cap *95*. This serves as a warning that there is appreciable pressure within the tank *t* and notifies the automobile driver or attendant that the cap *95* should not be completely removed without first relieving the pressure in the tank. The depending flange *101* of cap *95* fits loosely about neck *92* and, with the cap turned sufficiently to engage pin *99* into recess *100a*, disc *96* is raised slightly from the upper face of flange *97* so that the tank *t* is vented between neck *92* and the depending flange of cap *95*. This serves as a further warning that the cap should not be removed until the pressure within the tank *t* has been reduced to atmospheric pressure, or substantially so, which can be determined readily by the velocity of the vapor being vented or the cessation of flow of vapor out of the tank.

In the modification illustrated in Figure 5, the valve *62b* is similar to the valve *62a* of Figure 4 and need not be illustrated nor described in detail. Nipple *86*, which enters the casing beneath the diaphragm and at the valve seat side thereof, it being noted that valve *62b* is disposed vertically, is connected by a short length of hose *105* to a tube *106* opening into tank *t* and corresponding to the usual overflow tube commonly used in cooling systems normally open to the atmosphere, such as ordinarily used. Nipple *87*, which leads from the outlet side of the diaphragm, is connected by a short length of hose *75*.

107 to a vent tube 108. Valve 62b is thus, in effect, connected into the ordinary overflow tube used for a cooling system normally open to the atmosphere, which provides means for applying the valve with facility and expedition to a cooling system of ordinary type and thereby converting said system into a closed cooling system.

10 Valve 62c of Figure 7 is similar to valve 62b of Figure 5, with the exception that diaphragm 67 is provided with an air inlet opening 67a controlled by a needle valve 110 carried by a bimetallic thermostat strip 111, at one end thereof, this strip being secured, at its other end, 15 at 112, to the diaphragm. At ordinary operating temperatures, valve 110 is closed and the main valve 62c operates in the manner previously described. If the cooling system cools down to a temperature such as to create a partial vacuum therein, the thermostat strip 111 acts to open valve 110, admitting air from tube 87 and casing section 66a through opening 67a and thence through casing section 65a to tank t, and also acts as a pressure vent to vent to the atmosphere air displaced from the tank by expansion of the liquid in the preliminary warming up of the system.

In the modified form of valve 62d shown in Figure 8, a collar 115, of angle section, seats upon 30 and may be secured to the upper face of diaphragm 67b, this collar being interiorly threaded for reception of an exteriorly threaded annular valve member 116 which screws into the collar and is provided with a circumferential shoulder 117 which bears against the under face of diaphragm 67b. The diaphragm is thus clamped tightly between collar 115 and shoulder 117, valve member 116 being thus secured to the diaphragm for movement therewith. At its lower portion, member 116 is beveled from the opposite sides thereof to provide an element 116a of reduced thickness and which has edge contact with a flat valve seat at the upper end of a screw plug 118 screwing into an interiorly threaded collar 119 extending upwardly from lower casing section 65b. This plug 118 is provided, in the upper end thereof, with a central depression 120 corresponding to element 69b of valve 62c. By removing plug 118, access may be had to the valve chamber and the valve seat and member for cleaning, repair or replacement. The depression 120 is curved to conform in shape to the segment of a sphere so that particles of foreign materials, which might otherwise tend to collect upon the flat upper face of plug 118, and which enter the depression 120, are swept from this depression by vapors or gases passing between member 116 and seat member 118 and thence through the outlet port defined by member 116. Similarly, in valve 62c of Figure 7, element 69b provides a rounded depression from which particles of foreign materials are readily swept by vapors flowing under pressure into and through the valve member.

65 In the modified form of valve 62c, shown in Figure 9, a valve seat member 121 is supported from the top wall of upper casing section 66b by a pin 122 which screws through a ball 123 rockably mounted in a spherical socket structure 124 defined in part by element 125 of wall 66b and by member 126 secured to the upper face of this wall. Valve seat member 121 is of dished cross-section, being shaped to correspond to the segment of a sphere, and presents a rounded upper 70 face which has edge contact with valve element

68 of diaphragm 67. This renders the valve seat member and the associated valve element self-cleaning and effectively eliminates possibility of sticking together thereof due to corrosion or collection of foreign materials therebetween. By 5 turning pin 122, the valve seat member may be adjusted relative to the valve element 68 so as to set the valve to operate at any desired pressure, within limits. The ball mounting of pin 122 permits of swinging movement of valve seat member 10 121 so that this member is self-aligning relative to valve element 68, thus assuring proper contact between this element and its coacting seat member.

In Figure 6 I have illustrated an additional 15 modified form of means for filling the cooling system. An outlet neck n' extends from head d of the engine and is connected, at its upper end, to a T fitting 130. The upper end of fitting 130 is connected by a short length of hose 131 to an 20 inlet fitting 132 secured to, and opening into, top tank T of the radiator r. Neck 130a of fitting 130 is closed by a screw cap 133. The fitting 130 is so disposed that the upper end thereof is in the plane of the desired liquid level within the tank 25 T. This assures that liquid introduced into the system through neck 130a cannot extend above the desired level therein.

If desired, instead of having the thermostatically controlled vent valve mounted on the diaphragm of the main valve, as in Figure 7, the valve casing may be provided with an opening to atmosphere at the valve seat side of the diaphragm, this opening being controlled by a thermostatically actuated valve for admitting air to the 30 radiator to prevent the formation of an objectionable degree of vacuum therein. If desired, any suitable supplemental means may be provided for optionally closing the vent opening independently of the thermostatically operated valve 35 so as to prevent escape of vapors through this opening, or entry of air through the vent opening, at all times or as conditions may require. Furthermore, the vent opening referred to may be suitably positioned to prevent freezing of the main 40 valve, in that it may be disposed to drain moisture from the main valve casing.

In addition to the filler neck or filler tube closure means above referred to, I also contemplate providing a closure for the filler neck, 50 which closure is urged closed by yieldable means permitting displacement thereof for introducing cooling liquid into the system. In the event of there being appreciable pressure within the radiator tank or cooling system, this pressure will be 55 effective to hold the closure member tightly seated and to prevent opening thereof except by the exertion of unusual pressure thereon.

Various means may be employed for maintaining a proper expansion space within the cooling 60 system, preferably within the top tank of the radiator, though the means herein disclosed are preferable. The maintenance of this expansion space is desirable as rendering available air or vapor for discharge through the relief valve, upon 65 opening of the latter, thus assuring operation of this valve in proper manner to produce the audible signal above referred to.

Referring to Figures 10 to 13, inclusive, top tank t of the radiator is provided with a filler neck 135 70 formed as shown. A split band 136 is secured about neck 135 in a suitable manner, conveniently by screw means 137. Band 136 is provided with an offset 138 in which is disposed a short tube 138a, closed at its lower end, from which extends 75

an outlet tube 139. A flanged rubber thimble 140 is mounted in the upper end of tube 138a. The band 136 is further provided, at opposite sides of neck 135, with members 141 of L cross-section, each defining a depending flange 142. The lower edge of each flange 142 is shaped to provide a cam surface 143 having at one end a rectangular stop element 144 and, at its other end, an upwardly and outwardly tapering element 145, the inner end of which provides a vertical stop shoulder.

Neck 135 is closed by a cap 146 provided with oppositely disposed depending L-shaped fingers 147 which cooperate with flanges 142 for securing the cap in position. Cap 146 comprises a collar 148, provided at its upper edge with a bead 149 in which are disposed the peripheral edge portions of a cover plate 150 and an inner diaphragm 151, secured by crimping bead 149 tightly thereover. Plate 150 is provided with openings 152, for a purpose to be described presently. Diaphragm 151 is provided with a depressed central disc 153, constituting a valve, and is otherwise similar to the diaphragm 67 of Figure 2. It will be noted that the structure of cap 146, so far described, is, in general, quite similar to that of the valve of Figure 2.

Collar 148 extends upward from an integral disc 154 having a central depressed portion 155 provided with a central upturned interiorly threaded collar 156. A flanged tubular valve seat member 157, closed at its lower end, open at its upper end, and provided above collar 156 with radial ports 158, screws through collar 156, upward travel of this member being limited by flange 159 at the lower end thereof. Member 157 fits snugly through an upturned collar 160 at the center of a disc 161 having a depending peripheral flange 162 fitting snugly within collar 148 and seating upon the upper face of disc 154. Open ended tubes 163 are secured at their lower ends in the cup-shaped portion 155 of disc 154 and, at their upper ends, in disc 161. Tubes 163 serve to reinforce the discs, and also establish communication between the interior of neck 135 and the space between disc 161 and diaphragm 151.

Cap 146 is provided with a projection 164, as shown in Figure 13, plate 150 and discs 154 and 161 being shaped conformably. Disc 154 is provided, at the projection 164, with an opening 165 which, in the fully closed position of the cap, registers with the upper end of rubber thimble 140, the disc 154 seating tightly upon flange 140a of thimble 140, and forming there-with a fluid-tight closure about opening 164. If desired, the cover 146 may be of truly circular shape in plan and of sufficient diameter to have opening 164 register with the upper end of thimble 140, as will be obvious, in which case either the width of members 141 of band 136, or the length of the elements at the lower ends of fingers 147, would be correspondingly increased. Flange 140a of thimble 140 is provided with an extension 140b which seats upon tab 138b of offset 138 of band 136. An above 140a is disposed between discs 161 and 154, opening at its outer end through disc 154, adjacent opening 164, and opening at its inner end through the bottom of depressed portion 155 of disc 154.

With cap 146 in fully closed position, valve element 153 normally seats upon and closes the upper end of valve seat member 157. The latter member is a tight fit in collar 160, so as to prevent any objectionable leakage at that point, and ports 158 are located below disc 161. Under

normal conditions the interior of neck 135 is closed to tube 139. In the event the pressure within the radiator reaches the maximum predetermined by the diaphragm 151, the latter is forced upward, lifting valve member 153 from seat member 157, thus venting the radiator to atmosphere through tube 139. The diaphragm vibrates when valve member 153 is opened in this manner, producing an audible signal in the manner previously described. The openings 152 of cover plate 150 permit escape of air from beneath this plate so that the signal is readily audible to the driver of the automobile.

The cap 146 is applied by inserting one of the fingers 147 through the notch in band 136 below screw 137, as viewed in Figure 11, and inserting the other finger through the notch above offset 138, until the cap seats upon the neck 135, and then turning the cap clockwise as viewed from above. The cap is forced tightly upon the filler neck by fingers 147 shown in Figure 13, and the cooperating cam surfaces 143, stop elements 144 limiting turning movement of the cap. In the extreme clockwise position of cap 146, with fingers 147 contacting stop elements 144, opening 164 is in register with nipple 140, as previously noted. Preferably, an annular gasket 155 is mounted within cap 146, at the under side of disc 154, and seats upon flange 166 at the upper end of neck 135, forming a fluid-tight and pressure resistant closure with the flange. This gasket is of proper thickness such that disc 154 forms, with flange 140a of thimble 140, a fluid-tight closure about opening 164, in the manner above described, and the outer end of elbow 164a is sealed by extension 140b of flange 140a.

To remove cap 146 it is turned counterclockwise, as viewed from above, as will be understood. When but slight counterclockwise movement of the cap has occurred, the outer end of elbow 164a is disposed to the left of thimble 140, as viewed in Figure 11, so as to be open to the atmosphere. This vents the radiator to atmosphere at that point. In the event of appreciable pressure within the radiator, steam issuing from the elbow 164a condenses and becomes visible, thus giving a signal which is both visible and audible and serves as a warning that the cap should not be removed until the pressure within the radiator has been lowered. The cap 146 may remain in this position until the pressure within the radiator has been lowered to safe value, or may be turned clockwise sufficiently to align the outer end of the elbow with thimble 140, venting the radiator through tube 139. If the signal given by the initial turning of the cap 146 in opening direction is disregarded, the cap will be raised by the pressure beneath it, and, in the continued turning of the cap, fingers 147 will contact elements 145, preventing further turning of the cap. At this time the cap will be raised from the upper end of the neck, and steam issuing between the cap and the neck will be deflected downward along the neck giving a further audible and visual signal indicating pressure within the radiator and that the cap should not be removed. In order now to remove the cap, it has to be forced downward against the pressure beneath it sufficiently to bring the terminals of fingers 147 below elements 145. This serves as a third and last warning that the cap should not be removed until the pressure within the radiator has been lowered to a safe value.

The modification shown in Figure 14 is quite

- similar to that of Figures 10 to 13, inclusive. The tube 139a is disposed within neck 167, cap 146b is truly circular in plan, and opening 164b registers with the upper end of thimble 140, as before. The cap is provided with depending fingers cooperating with cam elements of a band 136a suitably secured about neck 167, as in Figs. 10 to 13, inclusive. If the cap is turned counter-clockwise a short distance, sufficient to permit 5 of its moving upward out of contact with thimble 140, or to dispose opening 164b so that it opens in part into thimble 140 and in part into neck 167, with appreciable pressure within the radiator, the latter is vented through tube 139a, giving 10 an audible signal readily heard, particularly if the engine is stopped. If turning of the cap in opening direction is continued, with appreciable pressure within the radiator, the cap will be raised from the neck, giving a visual and audible 15 signal, and complete removal of the cap, so long as the pressure persists, will be obstructed in the same manner as in Figures 10 to 13. The form shown in Figure 14 omits the elbow 164a and associated elements of Figures 10 to 13, as 20 being unnecessary due to the disposition of tube 139a within neck 166.
- It will be seen that in the forms of my invention shown in Figures 2, 4, 10 to 13, inclusive, and 14, I provide means for giving a visual and 25 an audible warning, at the upper end of the filler neck, where it cannot escape the attention of a person starting to remove the cap, when the pressure within the radiator is of such value as to render removal of the cap dangerous or objectionable. In certain forms, a further visual 30 and audible warning is given if the cap is moved further in opening direction, and complete opening of the cap is obstructed so long as appreciable pressure within the radiator persists.
- Preferably, I provide a strainer 168 at the under 35 face of portion 155 of disc 154. This strainer is of reticulated construction, provided at its outer edge with a sheet metal reinforcing annulus 169, crimped thereon; and has a central reinforcing annulus 170, also of sheet metal, crimped thereon, as shown in Figure 10. Valve seat member 157 passes through annulus 170, which is clamped between flange 159 and the under face of portion 155 of disc 154, for securing 40 the strainer in position. The strainer is concaved downward between members 169 and 170, to increase its effective area while rendering it self-cleaning, in that particles adhering to the under face of the strainer will be washed therefrom and returned to the radiator by gravity, by condensate passing downward through the strainer.
- Referring to Figure 10, the filler neck 135 is provided, at its lower end, with a flange 135a fitting 45 into a corresponding depression in the top wall of tank t and secured therein by soldering. It is inevitable that in the use of the automobile the radiator and associated parts are subjected to severe vibration, as well as heating tending to 50 soften the solder about the base of neck 135. It is important that any parts supported by the filler neck be not of any considerable weight, as otherwise the weight thereof and the vibration to which the parts are subjected would be apt to 55 soon pull the base of the filler neck loose from the wall of tank t. The cap 146 and associated parts are of sheet metal construction, as shown, which renders the device as a whole of exceptionally light weight, but of adequate strength, 60 and avoids danger of loosening of the filler neck.

Also, by having valve 153 of light weight I avoid likelihood of this valve vibrating in resonance with the neck and adjacent parts.

As above indicated, and as will be understood by those skilled in the art, various changes in construction and arrangement of parts of my invention may be resorted to without departing from the field and scope of the same, and I intend to include all such variations, as fall within the scope of the appended claims, in this application, in which the preferred forms only of my invention are disclosed.

What I claim is:

1. In an automobile, in combination with an internal combustion engine and a cooling system therefor normally closed to the atmosphere and including a radiator, a valve having a port for venting the system, said valve comprising a pressure responsive member of materially greater area than the valve port and normally acting to maintain the valve closed, said member being subject to the pressure within the system and actuated thereby to open the valve when said pressure exceeds a predetermined maximum.

2. In an automobile, in combination with an internal combustion engine and a cooling system therefor normally closed to the atmosphere and including a radiator, means for maintaining within the radiator an expansion chamber of at least a predetermined minimum extent, and a valve communicating with said chamber and having a port for venting it to atmosphere, said valve comprising a pressure responsive member of materially greater area than the valve port and normally acting to maintain the valve closed, said member being subject to the pressure within the chamber and actuated thereby to open the valve when said pressure exceeds a predetermined maximum.

3. In an automobile, in combination with an internal combustion engine and a cooling system therefor normally closed to the atmosphere and including a radiator, means for maintaining within the radiator an expansion chamber of at least a predetermined minimum extent, and a normally closed pressure responsive valve subject to the pressure in said expansion chamber and actuated thereby for venting the expansion chamber when the pressure exceeds a predetermined maximum.

4. In an automobile, in combination with an internal combustion engine and a cooling system therefor normally closed to the atmosphere and including a radiator, means for introducing cooling liquid into the system and for limiting the maximum height to which the liquid can be introduced into the radiator to provide therein an expansion chamber of predetermined minimum extent, and a normally closed pressure responsive valve subject to the pressure in said expansion chamber and actuated thereby for venting the expansion chamber when the pressure exceeds a predetermined maximum.

5. In an automobile, in combination with an internal combustion engine and a cooling system therefor normally closed to the atmosphere and including a radiator, a filling tube extending into the radiator and limiting filling thereof with a liquid to a predetermined level to provide within the radiator a liquid free space of predetermined minimum extent, a removable closure member for the tube, and a normally closed pressure responsive valve subject to the pressure in said space and actuated thereby for venting the space

when the pressure exceeds a predetermined maximum.

6. In an automobile, in combination with an internal combustion engine and a cooling system therefor normally closed to the atmosphere and including a radiator, a filling member for the radiator, a normally closed pressure responsive valve subject to the pressure in the radiator and actuated by said pressure for venting the radiator when the pressure therein exceeds a predetermined maximum value, a removable closure member for the filling member, and means for stopping removal of said closure member when there is appreciable pressure within the radiator.
10. In an automobile, in combination with an internal combustion engine and a cooling system therefor normally closed to the atmosphere and including a radiator, a filling member for the radiator, a normally closed pressure responsive valve subject to the pressure in the radiator and actuated by said pressure for venting the radiator when the pressure therein exceeds a predetermined maximum value, a removable closure member for the filling member, and means for stopping removal of said closure member when there is appreciable pressure within the radiator while permitting uninterrupted opening of the closure member sufficiently to vent the radiator between said closure member and the filling member.
15. In an automobile, in combination with an internal combustion engine and a cooling system therefor normally closed to the atmosphere and including a radiator, a filling member for the radiator, a normally closed pressure responsive valve subject to the pressure in the radiator and actuated by said pressure for venting the radiator when the pressure therein exceeds a predetermined maximum value, a removable closure member for the filling member, and means for

20. valve subject to the pressure in the radiator and actuated by said pressure for venting the radiator when the pressure therein exceeds a predetermined maximum value, a removable closure member for the filling member, and means for stopping removal of said closure member when there is appreciable pressure within the radiator while permitting uninterrupted opening of the closure member sufficiently to vent the radiator between said closure member and the filling member.
25. 8. In an automobile, in combination with an internal combustion engine and a cooling system therefor normally closed to the atmosphere and including a radiator, a filling tube for the radiator, a normally closed pressure responsive valve subject to the pressure in the radiator and actuated by said pressure for venting the radiator when the pressure therein exceeds a predetermined maximum value, and a removable closure member for the tube, said member and the tube having cooperating means for forming a fluid-tight and pressure-resistant closure therebetween when the member is in completely closed position and for venting the radiator when the closure member is moved a predetermined distance in opening direction.

30. 9. In an automobile, in combination with an internal combustion engine and a cooling system therefor normally closed to the atmosphere and including a radiator, a filling tube extending downward within the radiator, removable means for closing the outer end of the tube, a normally closed pressure responsive valve subject to the pressure in the radiator and actuated by said pressure for venting the radiator when the pressure therein exceeds a predetermined maximum value, and means responsive to pressure in the radiator for closing said tube to the interior of the radiator when there is appreciably greater pressure within the latter than in the former.

35. 10. In an automobile, in combination with an internal combustion engine and a cooling system therefor normally closed to the atmosphere and including a radiator, means for automatically supplying a cooling liquid to the radiator and for maintaining the liquid at a predetermined level within the radiator to provide within the latter an extension space of predetermined extent, and a normally closed pressure responsive valve subject to the pressure in the radiator and actuated by said pressure for venting the radiator when the pressure therein exceeds a predetermined maximum value.

40. 11. In an automobile, in combination with an

internal combustion engine and a cooling system therefor normally closed to the atmosphere and including a radiator, means for automatically supplying a cooling liquid to the radiator and for maintaining the liquid at a predetermined level within the radiator to provide within the latter an extension space of predetermined extent, a normally closed pressure responsive valve subject to the pressure in the radiator and actuated by said pressure for venting the radiator when the pressure therein exceeds a predetermined maximum value, and means responsive to the temperature of the cooling system for disabling the liquid supplying means when the temperature of the system is below a predetermined low temperature and enabling said supplying means when the cooling system is at or above said predetermined temperature.

12. In an automobile, in combination with an internal combustion engine and a cooling system therefor normally closed to the atmosphere and including a radiator, means for automatically supplying a cooling liquid to the radiator and for maintaining the liquid at a predetermined level within the radiator, and means responsive to the temperature of the cooling system for disabling the liquid supplying means when the temperature of the system is below a predetermined low temperature and enabling said supplying means when the cooling system is at or above said predetermined temperature.

13. In an automobile, in combination with an internal combustion engine and a cooling system therefor normally closed to the atmosphere and including a radiator, a normally closed pressure responsive valve subject to the pressure in the radiator and actuated by said pressure for venting the radiator when the pressure therein exceeds a predetermined maximum value, and a movable wall subject to the pressure within the system and accessible for operating mechanisms supplemental thereto.

14. In an automobile, in combination with an internal combustion engine and a cooling system therefor normally closed to the atmosphere and including a radiator, a normally closed pressure responsive valve subject to the pressure in the radiator and actuated by said pressure for venting the radiator when the pressure therein exceeds a predetermined maximum value, and means responsive to the temperature of the cooling system for admitting air thereto when said system is at or below a predetermined low temperature.

15. In an automobile, in combination with an internal combustion engine and a cooling system therefor normally closed to the atmosphere and including a radiator, a normally closed pressure responsive valve subject to the pressure in the radiator and actuated by said pressure for venting the radiator when the pressure therein exceeds a predetermined maximum value, and means responsive to the temperature of the cooling system for admitting air thereto when said system is at or below a predetermined low temperature, said means establishing free communication between the system and the atmosphere when said system is at or below said predetermined temperature.

16. In an automobile, in combination with an internal combustion engine and a cooling system therefor normally closed to the atmosphere and including a radiator having a top tank, a cup-like casing having an outwardly projecting peripheral flange adapted for seating in a corre-

- sponding depression in a wall of the tank contiguous to an opening through said wall to accommodate the body of the casing, a cupped diaphragm fitting in and extending across the casing and forming a fluid tight closure therewith, said diaphragm having a peripheral flange extending into the flange of the casing and secured therein, and two cooperating valve members disposed centrally of the diaphragm and the casing at the side of the latter disposed within said tank, one of said members defining an outlet opening and the other controlling said opening, said casing being provided through said side thereof with an inlet opening for admitting fluid under variable pressure from said tank into said casing, the effective cross-area of said outlet opening being at least as great as the effective cross-area of the inlet opening.
17. In an automobile, in combination, an internal combustion engine and a cooling system therefor closed to the atmosphere, and a movable wall subject to the pressure within the system and accessible for operating mechanisms supplemental thereto.
18. In an automobile, in combination with an internal combustion engine and a cooling system therefor normally closed to the atmosphere and including a radiator, means for limiting the level of cooling liquid within said system for maintaining therein an expansion space of at least a predetermined minimum extent, a valve housing open to said space for receiving therefrom fluid under pressure, a substantially horizontal outlet tube exterior of and leading from said housing, and a normally closed pressure responsive valve within said housing controlling communication between said space and said outlet tube, said valve being disposed above the normal liquid level in said system.
19. In combination with a radiator intended for use with an automobile internal combustion engine cooling system at all times normally closed to the atmosphere, said radiator comprising a top tank having a top wall, a valve housing disposed in proximity to said top wall and open to said tank for receiving therefrom fluid under pressure, a substantially horizontal outlet tube exterior of and leading from said housing, said tube being in close proximity to said top wall and said housing being of slight height relative to its width, and a normally closed pressure responsive valve within said housing controlling communication between said tank and said outlet tube, said valve being disposed above the normal level of cooling liquid in said radiator.
20. In an automobile, in combination with an internal combustion engine and a cooling system therefor normally closed to the atmosphere and including a radiator, a filling member for the radiator, a normally closed pressure responsive valve subject to the pressure in the radiator and actuated by said pressure for venting the radiator when the pressure therein exceeds a predetermined maximum value, a removable closure member for the filling member, and means for limiting removal of said closure member when there is appreciable pressure within the radiator while permitting opening of the closure member sufficiently to vent the radiator to atmosphere
- between said closure member and the upper end of said filling member.
21. In combination with a radiator for use in an internal combustion engine cooling system, a filling member for the radiator, a removable closure member for the filling member, and means for obstructing removal of said closure member when there is appreciable pressure within the radiator while permitting opening of the closure member sufficiently to vent the 10 radiator.
22. In combination with an internal combustion engine and a cooling system therefor including a radiator, a filling member for the radiator, a removable closure member for the filling member, and means for stopping removal of said closure member when there is appreciable pressure within the radiator, while permitting uninterrupted opening of the closure member sufficiently to vent the radiator between said closure member and the filling member.
23. In combination with an internal combustion engine and a cooling system therefor including a radiator, a filling tube for the radiator, and a removable closure cap for the tube extending thereacross, said cap and said tube having cooperating means for forming a fluid tight and pressure resistant closure therebetween when said cap is in completely closed position, and for venting the radiator when said closure 30 cap is moved a predetermined distance in opening direction.
24. In combination with a radiator intended for use in an internal combustion engine cooling system normally closed to the atmosphere, a filling member for the radiator, a normally closed pressure responsive valve subject to the pressure within the radiator for venting the latter when the pressure therein reaches a predetermined maximum value, a removable closure member for the filling member, and means effective for obstructing removal of said closure member when there is appreciable pressure within the radiator.
25. In combination with a radiator intended for use in an internal combustion engine cooling system normally closed to the atmosphere, a normally closed pressure responsive valve subject to the pressure within the radiator for venting the latter when the pressure therein reaches a predetermined maximum value, and a movable wall subject to the pressure within the radiator.
26. In combination, a radiator intended for use in an internal combustion engine cooling system normally closed to the atmosphere, and a movable wall subject to the pressure within the radiator.
27. In combination with an internal combustion engine and a cooling system therefor normally closed to the atmosphere and including a radiator, means for limiting the level of cooling liquid within said system for maintaining therein an expansion space of at least a predetermined minimum extent, means for venting said space, and a normally closed pressure responsive valve controlling communication between said space and said venting means, said valve being disposed above the normal liquid level in said system.
